CATHETER WITH FLOW CONTROL VALVE

Charles B. McNeil, North Kingstown, and Paul Hanifi,
Warwick, R.I., and Norman La Pine, Putnam, Conn.,
assignors to International Paper Company, New York,
N.Y.

Filed Apr. 15, 1975, Ser. No. 568,203

Term of patent 14 years

Int. Cl. D24—02, 04
U.S. Cl. D83—12 A

FIG. 4

FIG. 5

FIG. 1 is a perspective view of a catheter with a flow control valve embodying our new design.

FIG. 2 is a side elevational view of the catheter of FIG. 1.

FIG. 3 is an end view of the catheter of FIG. 1.

FIG. 4 is a top plan view of the catheter of FIG. 1.

FIG. 5 is a bottom plan view of the catheter of FIG. 1. The catheter is broken away for convenience of illustration.

We claim:

The ornamental design for a catheter with flow control valve, as shown and described.
